The ornamental design for a headlamp bezel for a motor vehicle, as shown and described.

DESCRIPTION

FIG. 1 is a perspective view of our headlamp bezel for a motor vehicle;

FIG. 2 is a top view thereof;

FIG. 3 is a front view thereof;

FIG. 4 is a back view thereof;

FIG. 5 is a bottom view thereof;

FIG. 6 is a left side view thereof; and,

FIG. 7 is a right side view thereof.

The design envisioned contains a second portion whose image is mirror symmetrical to the one shown. The embodiment shown is for the left side of the vehicle.
